(57) **CLAIM**

The ornamental design for a bridge and gondola system, as shown and described.

DESCRIPTION

FIG. 1 is a top plan view of a bridge and gondola showing my new design;

FIG. 2 is an enlarged top plan view of a first aspect thereof taken along line 2 of the circled portion in FIG. 1;

FIG. 3 is an enlarged top plan view of a second aspect thereof taken along line 3 of the circled portion in FIG. 1;

FIG. 4 is an enlarged top plan view of a third aspect thereof taken along line 4 of the circled portion in FIG. 1;

FIG. 5 is a side elevation view of a fourth aspect thereof taken along line 5 of the circled portion in FIG. 1;

FIG. 6 is a side elevation view of a fifth aspect thereof taken along line 6 of the circled portion in FIG. 1;

FIG. 7 is an enlarged side elevation view of the left portion thereof taken along line 7 of the circled portion in FIG. 5;

FIG. 8 is an enlarged side elevation view of the right portion thereof taken along line 8 of the circled portion in FIG. 5;

FIG. 9 is an enlarged side elevation view of the center portion thereof taken along line 9 of the circled portion in FIG. 6;

FIG. 10 is an enlarged side elevation view of the right portion thereof taken along line 10 of the circled portion in FIG. 6;

FIG. 11 is an enlarged side elevation view of a portion of the gondola;

FIG. 12 is a cross-sectional view thereof with both doors open taken along line 12 of FIG. 14;

FIG. 13 is a cross-sectional view thereof with the right door open taken along line 13 of FIG. 14;

FIG. 14 is a cross-sectional view thereof showing a first seating arrangement in phantom taken along line 14 of FIG. 11;

FIG. 15 is a side elevational view of an enlarged portion of the bridge and gondola system at the end point shown in FIG. 7 with a side view of two gondolas; and,

FIG. 16 is a side elevational view of an enlarged portion of the bridge and gondola system at the midpoint of FIG. 9 with a side view of two gondolas.

The broken line showing of land, buildings, trees, ports, docks and water in FIGS. 1-10 and seating in FIGS. 12-14 is included for the purpose of showing environmental portions of the bridge and gondola system and forms no part of the claimed design.
